US00D830346S

(12) **United States Design Patent** (10) **Patent No.:** **US D830,346 S**
Chen (45) **Date of Patent:** **** Oct. 9, 2018**

(54) **TELEPHONE TYPE COMPUTER
MICROPHONE**

(71) Applicant: **Ching-Wen Chen**, Taipei (TW)

(72) Inventor: **Ching-Wen Chen**, Taipei (TW)

(**) Term: **15 Years**

(21) Appl. No.: **29/604,085**

(22) Filed: **May 15, 2017**

(51) **LOC (11) Cl.** **14-01**

(52) **U.S. Cl.**

USPC **D14/225**

CLAIM

The ornamental design for a telephone type computer microphone, as shown and described.

DESCRIPTION

FIG. 1 is a perspective view of telephone type computer microphone showing my new design;

FIG. 2 is a front view thereof;

FIG. 3 is a rear view thereof; and

FIG. 4 is a left side elevational view thereof;

FIG. 5 is a top elevational view thereof; and,

FIG. 6 is a bottom elevational view thereof.

1 Claim, 5 Drawing Sheets
